HAIR CURLER

Filed May 24, 1946

UNITED STATES PATENT OFFICE

2,542,601

HAIR CURLER

Paul Van Cleef, Chicago, Ill., assignor, by mesne assignments, to Johns-Manville Corporation, New York, N. Y., a corporation of New York

Application May 24, 1946, Serial No. 671,936

4 Claims. (Cl. 132—43)

1

The present invention relates generally to hair curlers. More particularly the invention relates to that type of hair curler which is adapted to have a lock of hair wound or wrapped around the central portion thereof and its ends bent inwards in side by side relation in order to hold the lock of hair against unwinding while the curler is in use on the user's head, and as its component parts comprises an elongated body of soft, readily compressible sponge rubber and an elongated soft metal core disposed in, and extending longitudinally through, the central portion of the body.

As evidenced by United States Patent No. 2,061,817, granted to me on November 24, 1936, it has heretofore been proposed in connection with a hair curler of the aforementioned type to make the body of sponge rubber truly cylindrical from end to end and to have the core of soft metal of uniform width from end to end and of such length that its end extremities terminate directly inwards of the ends of the body. In practice it has been found that a curler like that of the aforementioned patent is subject to several objections. In the first place repeated use of the curler often results in the core shifting lengthwise with respect to the body and in some cases the extent of lengthwise shift of the core is such as to cause one end of the core to project through the adjacent end of the body. Should the core work its way through one end of the body the projecting or exposed end is likely to scratch or otherwise injure the user of the curler. Another objection to a hair curler like that of patent No. 2,961,817 is that the lock of hair that is wound around the central portion of the curler tends in connection with wearing or use of the curler to spread due to the fact that the body is truly cylindrical from end to end and hence the ends of the body cannot restrain spreading of the lock with respect to the central portion of the curler.

The primary object of the invention is to provide a hair curler which is an improvement upon, and eliminates the defects of, previously designed hair curlers of the same general type or character and is characterized by the fact that (1) the ends of the soft metal core are shaped to form enlargements which preclude the core from sliding or working its way through the body; and (2) the ends of the sponge rubber body are shaped to form knobs which when the curler is in use prevent the lock of hair from spreading.

Another object of the invention is to provide a hair curler which is generally of new and improved construction, effectively and efficiently

2

fulfills its intended purpose, possesses a comparatively long life and is capable of being manufactured at a low or reasonable cost.

Other objects of the invention and the various advantages and characteristics of the present hair curler will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective showing a hair curler embodying one form of the invention, with a lock of hair wound around the central portion thereof but before inward bending of the curler ends;

Figure 2 is a perspective showing the curler of Figure 1 after the ends thereof have been bent inwards into such side by side relation as to hold the curler in place with respect to the lock of hair;

Figure 3 is a longitudinal section of the curler of Figures 1 and 2, illustrating in detail the manner in which the ends of the soft metal core are bent or shaped to form enlargements whereby the core is precluded from lengthwise shift relatively to the sponge rubber body;

Figure 4 is a longitudinal section of a hair curler embodying a second or modified form of the invention; and

Figure 5 is an enlarged transverse section on the line 5—5 of Figure 4.

The hair curler which is shown in Figures 1, 2, and 3 of the drawing constitutes one form or embodiment of the invention. It is adapted, as shown in Figure 1, to have a lock of hair wrapped around the central portion thereof and comprises as its components or parts an elongated body 10 and a core 11. The body is formed of soft readily compressible sponge or solid natural or synthetic rubber and is preferably molded around the core. It is of such length that when a lock of hair is wound around its central portion the ends thereof project outwards a sufficient distance beyond the hair to permit them to be bent inwards, as shown in Figure 2, into a position wherein they are in side by side relation and serve to hold the lock of hair against unwinding while the curler is in use on the user's head. All portions of the body, with the exception of the end extremities, are preferably circular in cross

section and are of uniform width or diameter. The end extremities of the body 10 are enlarged in order to form knobs 12. The latter are either spherical or ellipsoidal in contour and are preferably but of slightly greater width than the other portions of the body. They have a twofold purpose in that they form handles whereby the curler may be readily gripped in connection with winding or wrapping of the lock of hair therearound and serve when the ends of the curler are bent inwards, as shown in Figure 2, to prevent the lock of hair on the central portion of the body from spreading. The core 11 is in the form of a length of aluminum wire or other soft, pliable metal and extends longitudinally through the center of the sponge rubber body. The ends of the core 11 are disposed within the knobs 12 and are bent so as to form loops 13. The latter have a twofold purpose in that they reinforce or strengthen the knobs 12 at the ends of the sponge rubber body 10 and serve to prevent the core 11 as a whole from sliding or working longitudinally through the body in connection with repeated use of the curler. If the knobs 12 are spherical the loops 13 are preferably formed so that they are circular so far as shape or conformation is concerned. If the knobs 12 are ellipsoidal the loops 13 are shaped correspondingly. When the curler is in its straight or unused position the loops 13 lie in the same plane as the central portion of the core. In other words, the loops 13 are disposed in parallel relation with the portion of the core that is intermediate the looped core ends. Because of the fact that the core 11 is formed of soft pliable metal the ends of the curler may be readily bent inwards as shown in Figure 2 and when so bent are yieldingly held in place by the end portions of the core.

In using the curler of Figures 1 to 3, inclusive, in connection with curling of a lock of hair the outer end of the lock is first wrapped tightly around the central portion of the body 10. Thereafter the curler is rolled so as to cause the lock to be completely or fully wrapped around the body as shown in Figure 1. After wrapping of the lock of hair around the central portion of the body 10 the ends of the curler are bent inwards into the position shown in Figure 2. When the curler is in use with the ends thereof in side by side relation the knobs 12 at the ends of the body are in straddled relation with the side portions of the lock of hair and hence prevent the lock from spreading. When it is desired to remove the curler from the lock of hair the inwardly bent ends are spread apart into their normal position and the lock of hair is unwound from the central portion of the body.

The curler which is shown in Figures 1 to 3, inclusive, is essentially simple in design and may be produced at a comparatively low cost. It has comparatively long life and this is due to the fact that the loops 13 constituting the enlargements at the ends of the soft metal core 11 prevent the core from sliding longitudinally out of place relatively to the sponge rubber body 10. By reason of the fact that the body 10 has the knobs 12 at its ends it may be readily gripped or handled in connection with wrapping of a lock of hair therearound.

The hair curler which is shown in Figures 4 and 5 of the drawing constitutes a second form or embodiment of the invention. It functions in the same manner as the hair curler of Figures 1 to 3, inclusive, and comprises an elongated

body 14 and a core 15. The body 14 is formed of soft readily compressible sponge rubber and is uniformly cylindrical throughout except for its ends. The ends of the body are enlarged to form circular or disc-like knobs 16. The latter function in the same manner and serve the same purpose as the knobs 12 at the ends of the body 10 of the curler of Figures 1 to 3, inclusive. The core 15, like the core 11, is formed of aluminum wire or other soft pliable metal. It extends centrally through the body 14 and has its ends disposed within the knobs 16. The ends of the core 15 are bent to form circular loops 17 and these extend at right angles to the intermediate portion of the core and are located centrally and concentrically within the disc-like knobs 16. The loops 17 function in the same manner as the loops 13 in that they serve to reinforce or strengthen the knobs 16 and prevent the core 15 from sliding or shifting longitudinally with respect to the sponge rubber body 14.

The invention is not to be understood as restricted to the details set forth since these may be modified within the scope of the appended claims without departing from the spirit and scope of the invention.

Having thus described the invention what I claim as new and desire to secure by Letters Patent is:

1. As a new article of manufacture, a hair curler comprising an elongated body formed of molded flexible rubbery material, adapted to have a lock of hair wound around its central portion and its ends bent inwards into lapped relation with the lock of hair so as to hold the latter in place on the curler, and embodying enlarged knobs at its end extremities, and a pliable core extending longitudinally through the body, adapted yieldingly to retain the ends of the body in their bent position, and having its ends terminating within the knobs and shaped to form enlargements that are embedded wholly within said knobs and serve to prevent the core from sliding longitudinally with respect to the body to such extent that it protrudes therethrough.
2. As a new article of manufacture, a hair curler comprising an elongated body formed of molded flexible rubbery material, adapted to have a lock of hair wound around its central portion and its ends bent inwards into lapped relation with the lock of hair so as to hold the latter in place on the curler, and embodying enlarged knobs at its end extremities, and a pliable core extending longitudinally through the body, adapted yieldingly to retain the ends of the body in their bent position, and having its ends terminating within the knobs and bent to form loops that are embedded wholly within said knobs and serve to prevent the core from sliding longitudinally with respect to the body to such extent that it protrudes therethrough.
3. As a new article of manufacture, a hair curler comprising an elongated body formed of molded flexible rubbery material, adapted to have a lock of hair wound around its central portion and its ends bent inwards into lapped relation with the lock of hair so as to hold the latter in place on the curler, and embodying substantially spherical knobs at the end extremities, and a pliable core extending longitudinally through the body, adapted yieldingly to retain the ends of the body in their bent position, and having its ends terminating within the knobs and bent to form loops that are embedded wholly within said knobs and serve to

prevent the core from sliding longitudinally with respect to the body to such extent that it protrudes therethrough.

4. As a new article of manufacture, a hair curler comprising an elongated body formed of molded flexible rubbery material, adapted to have a lock of hair wound around its central portion and its ends bent inwards into lapped relation with the lock of hair so as to hold the latter in place on the curler, and embodying at its end extremities enlarged disc-like knobs, and a pliable core extending longitudinally through the body, adapted yieldingly to retain the ends of the body in their bent position, and having its ends terminating within the knobs and bent to form substantially circular right angle loops

that are embedded wholly within said knobs and serve to prevent the core from sliding longitudinally with respect to the body to such an extent that it protrudes therethrough.
